HOSPITAL BED LIGHT FIXTURE AND SERVICE CONSOLE

Marcus Bodian, Los Angeles, Calif., assignor to Sunbeam Lighting Co., Inc., a corporation of California

Filed Dec. 6, 1965, Ser. No. 89

Term of patent 14 years

(Cl. D48—20)

FIG. 1 is a front elevation view of a combined hospital bed light fixture and service outlet console showing my new design;

FIG. 2 is a top plan view of the same;

FIG. 3 is a bottom view of the same;

FIG. 4 is an end elevational view of the same taken from the position indicated by the line 4—4 of FIG. 1; and

FIG. 5 is an end elevational view of the same taken from the position indicated by the line 5—5 of FIG. 1.

The rear of design is substantially plane and unornamented.

I claim:

The ornamental design for a hospital bed light fixture and service console, as shown and described.
